WATCHMAN'S SIGNAL AND ALARM SYSTEM

Harold Machinist, Chicago, Ill., assignor to Dudley Lock Corporation, Chicago, Ill., a corporation of Illinois

Application December 13, 1938, Serial No. 245,461

10 Claims. (Cl. 177—360)

This invention relates to an improved construction for a watchman's signal box and operating means therefor, and to an improved arrangement of a series of such boxes in a system.

5 One object of the invention is to provide a series of boxes with at least one box in the series associated with a signal mechanism arranged to record at a remote point the fact that the box has been operated in accordance with the watch-

10 man's routine; the remaining boxes include features so related to the operating handle employed by the watchman that he must necessarily visit the stations at which these boxes are located in a certain predetermined order before he can em-

15 ploy the handle for operating the signal-transmitting box of the series. Another object of the invention is to provide a changeable mechanism for the handle susceptible of a wide variety of changes, and easily modified to produce changes

20 in a different order so that the mechanism can be installed in a large number of buildings and factories without any danger that the handle employed in one system will operate in another system of the same general type. Another object is to provide a system in which the means for altering the operating handle at each box of a series shall include lock and key mechanism not easily duplicated. Other objects will appear as the description proceeds. The invention consists of the various features and elements of construction and in their cooperative arrangement in a system, as herein shown and described and as indicated by the claims.

35 In the drawings:

Figure 1 is a perspective view of the exterior of a watchman's signal box and an operating handle therefor embodying this invention.

Figure 2 is a view of the mechanism housed in the box, as seen from the inner side of the cover and with certain parts shown in section to reveal details of construction.

Figure 3 is a vertical section taken through the interior housing for the signal winding gear at a plane just back of the face plate of the box, and showing the gear and its associated pocket which receives the operating handle.

Figure 4 is a vertical section taken substantially as indicated at line 4—4 on Figure 3.

50 Figure 5 is an end elevation of the operating handle.

Figure 6 is a side elevation of the operating handle.

Figure 7 is an axial section on an enlarged scale, taken as indicated at line 7—7 on Figure 5.

Figure 8 is a transverse section taken as indicated at line 8—8 on Figure 7.

Figure 9 is a horizontal section taken through the signal box, as indicated at line 9—9 on Figure 2 and showing a portion of the operating handle in position to be entered in the cooperating pocket of the gear.

Figure 10 is a face view of an intermediate box of the system having no signal mechanism associated therewith.

Figure 11 is a vertical section taken as indicated at line 11—11 on Figure 10.

Figure 12 is a sectional view similar to Figure 11, showing a special alarm box employed as a supplemental element of the system.

Figure 13 is a transverse section taken as indicated at line 13—13 on Figure 12.

Figure 14 is a fragmentary section similar to Figure 4 but showing a modification of certain features.

For the purpose of insuring that a watchman is making his regular rounds at the proper intervals, and is inspecting the premises thoroughly on each round, there have been various systems devised by which the watchman is required to operate one or more signal devices which make a record of his visits to the points at which such devices are operable; and, particularly where the watchman is employed by an outside agency which guarantees the efficiency of his services,

it is customary to arrange for the operation of such signal devices at a remote point, such as a control office of the agency where reports are received periodically from all watchmen in the service. The present invention relates to such a system, and includes various means and devices intended to require and insure that the watch-

man shall follow a predetermined routine, and that any deviation from his prescribed procedure shall be promptly indicated at the central office receiving reports from the system.

An important element of the system is the signal box 1, having a removable face plate 2, normally secured by a key-operated lock 3 and having an opening 4 for the introduction of an operating handle 5, which is carried by the watch-

man on his rounds, and which is similarly em-

ployed in each box of the system. As seen in Figure 2, the box 1 encloses a signal-operating mechanism 6, which may be of any standard con-

struction, and need not be described in detail, but which will usually include a spring-wound motor and gear train (not seen in Figure 2) for rotating a toothed wheel 7 through one complete turn to

actuate spring contact arms 8, 8 for sending

electrical signals through any suitable signal circuit by means of wires (not shown) connected to said contact arms 8, 8 and leading from the box 1, preferably in concealed fashion, as through 5 the panel or partition wall in which the box is installed.

The mechanism 6 includes a winding shaft 9 having mounted thereon a segment gear 10 whose teeth are positioned to mesh with the teeth of a 10 mutilated gear 11 journaled for rotation within the box 1 and enclosed in a separate interior casing of its own, seen at 12. The back wall 13 of the case 12 is formed with a central, inwardly projecting hub 14 which serves as a bearing for 15 the gear member 11 and said member includes an integrally formed pocket having a cylindrical portion 15 with a pair of laterally extending parallel walls 16 embracing a space adjacent said cylindrical portion, as seen in Figure 3. The 20 space enclosed by the portions 15 and 16 corresponds in cross-section substantially to the shape of the opening 4 in the face plate 2 of the box 1 and is of substantially the cross-section of the operating handle 5, shown in perspective in 25 Figure 1.

When the handle 5 is inserted through the opening 4 into the pocket of the gear member 11 and is turned once around, it rotates the gear and causes it first to mesh with the teeth of the 30 segment 10 and swing the latter through a limited arc in the direction for tensioning the spring of the mechanism 6. The mechanism then begins to operate somewhat in the manner of a clock train at a speed controlled by a fly-ball governor 35 seen at 17. While the spring-wound train is operating, and actuating the electrical contacts 8, 8, the shaft 9 rotates in the reverse direction, swinging the segment back to its initial position. This is permitted because of the mutilated nature 40 of gear 11, which has only enough teeth to mesh with all the teeth of the segment 10, and which, beyond that point, is of circular outline of a radius to clear the teeth of segment 10, if the latter should commence its return swing while the 45 single rotation of the gear member 11 is being completed. In any event, a single turn of the member 11 terminates with its first tooth just outside the path of the teeth of segment 10, this being the position at which the handle 5 can be 50 withdrawn through the opening 4. Thus the gear 11 is left out of mesh with segment 10, but in the position to pick up the segment in the initial portion of its next turn when again operated by the handle 5.

55 The operating handle 5 includes a cylindrical body portion 20 with a rectangular portion 21 extending from one side of the cylinder, and a hand-grip 22 secured in the end of the cylinder. The opposite end of the cylinder 20 exposes the 60 key-slot 23 of a key-operated cylinder lock, which may be of the pin tumbler type, and which is preferably of the type covered by U. S. Patent No. 2,030,836, since this lock employs a key having several unrelated cam surfaces so arranged 65 as to render duplication of the key unusually difficult. The cylinder 24 of such a lock is seen in Figure 7, with the pin tumblers 25 of the plug 24^a engaged in suitable slots or apertures of the cylinder. At the inner end the key plug carries 70 a disk 26, shown with one tooth 27 projecting for engagement with the teeth of a ratchet-type gear wheel 28, which is journaled in the laterally projecting portion 21 of the handle body.

This portion 21 of the handle is formed at its 75 outer edge with a plurality of recesses or notches

29, and the cylindrical interior surface of the housing 12 is provided with arcuate ribs 18, whose leading ends 19 merge obliquely into the cylindrical surface of the housing 12. These ribs 18 are spaced apart so as to interengage with certain of the notches or recesses 29 when the handle member is inserted through the opening 4. But into each of the recesses 29 there projects from the interior of the body 21 a small plunger 30, normally held in projecting position by a spring 31. And certain of said plungers are locked in projecting position by means of a cylinder 32 rotatably mounted in the body 21 in co-axial and operative engagement with the ratchet wheel 28. This cylinder 32 is formed with openings 33 distributed over its surface so that at any given adjustment of the cylinder 32 about its axis certain of said openings will be aligned with certain of the plungers 30, so as to permit them to be 15 yieldingly depressed against the force of their 20 respective springs 31. In the system herein illustrated the body portion 21 of the handle member is provided with five notches 29 and the cylinder 32 is arranged with openings or 25 recesses 33 in groups of two, so that at any position of its adjustment it is possible for two of the plungers 30 to be yieldingly depressed. Thus, in order for the handle to be rotatable in the 30 housing 12 of the box 1, the two plungers 30 which register with the ribs 18 in said housing 35 must be rendered yieldable by proper adjustment of the cylinder 32. When this condition is fulfilled, the handle member 5 may be inserted in the opening 4 and, as it enters the pocket of the gear member 11, a fixed key 34, anchored in 40 the boss 14 of the housing 12, will register with the key-slot 23, which is exposed in the end of the handle body 20. When the handle is thrust in to its limit this key 34 will properly register with the tumblers 25 of the cylinder lock, and as 45 the handle member is turned in the housing 12 the fixed key 34 will cause rotation of the plug of the cylinder lock through one complete turn. This will have the effect of turning the disk 26 through one turn, so that its single tooth 27 will 50 engage one tooth of the ratchet gear 28 and will turn that gear through an angle corresponding to one tooth, at which position it will be arrested by a detent pawl 36, urged into engagement with the wheel 28 by a spring 37. As the 55 handle 5 is turned in the housing 12, two of its notches 29 interengage with the ribs 18, the yieldable plungers 30 in those notches being depressed as they ride over the inclined approaches 19 of the ribs 18; but these ribs extend only 60 through the first portion of the rotation and terminate at 38, thus permitting the plungers 30 to be projected by their springs 31 and to disengage themselves from the registered openings in the cylinder 32. Thereafter, the tooth 27 65 sweeps into engagement with a tooth of the ratchet wheel 28 and turns the cylinder 32 through the angle of a single tooth of the ratchet wheel, thus bringing a different pair of openings 33 into alignment with the plungers 30. 70 Therefore, when the handle 5 is removed from the first box 1 of the series, its rotation in that box cannot be repeated immediately, because the recesses 29, which register with ribs 18, are now blocked by plungers 30, which cannot be 75 depressed. But the plungers which have been released by alignment with a second set of holes 33 in the cylinder 32 are those corresponding to the ribs 18^a of the second box 40 of the series, as seen in Figures 10 and 11. This second box 80

40 need not include any signal mechanism like that shown in the first box 1. Its only function is to insure that the watchman shall visit the station at which the second box is located after 5 he leaves the station at which box 1 is located. The box 40 includes a central boss 14^a projecting from its back wall 13^a and a key 34^a, identical with the key 34, is anchored in the boss 14^a in position to engage the key slot 23 of the handle 10 member 5 when the latter is inserted in the box 40. The ribs 18^a permit one turn of the handle member 5 in the box 40, but upon the completion of that turn the plug of the cylinder lock 24 will have been rotated through one revolution, so that the tooth 27 of disk 26 will have 15 shifted the cylinder 32 by the amount of one tooth of the ratchet wheel 28, thus bringing into alignment with the plungers 30 a third set of openings 33. This action automatically blocks 20 the plungers 30, corresponding to the ribs 18^a, so as to prevent further rotation of the handle member in the box 40, but prepares a different pair of plungers 30 to yield upon being aligned with the differently placed ribs in the next succeeding 25 box, which may be exactly similar to the box 40, except for the arrangement of the ward ribs therein.

Thus the watchman will travel from station to station, inserting the handle member 5 successively in boxes of the type of the box 40, turning the handle through one revolution in each box and thus re-adjusting the plungers 30 for operation in the next succeeding box. After visiting every station of the series he may return to the 30 initial station which is provided with box 1, and upon inserting the handle in that box, and operating it, he will thus send a second signal to the central office, indicating that he has completed his rounds.

40 Or, if preferred—and particularly if the premises are such that the watchman can make his complete rounds in a few minutes, but is not required to repeat his inspection at once, or for a considerable period of time—a second signaling 45 station like that housed in the box 1 may be located at the end of the series, so that the second report signal is turned in by the watchman upon the completion of the series, and without returning to the initial station. This will provide 50 for a close check-up on the time occupied by the watchman in visiting the complete series of stations without adding in the time which it takes him to return from the last to the initial station. But in many instances a single signal 55 mechanism will serve the purpose.

Occasionally, in connection with the perpetration of a hold-up or a burglary, the watchman is forced by one member of the gang to make his regular rounds so as to turn in signals to the 60 central office at the expected intervals and avoid arousing suspicion. To meet such emergencies I provide a special alarm box 50, which is exactly like the box 40 in external appearance, when installed, but in which the key member 34^x, instead of being fixedly mounted, is secured in a central box 51 formed on the inner end wall of a pocket 52, 53, which is shaped like the pocket 15, 16 of the box 1, or like the pockets 15^x, 16^x of the box 40, so as to receive the handle member 5. The end wall or flange 54 of the pocket in box 50 has a centering hub 55 which is journaled in a recess in the back wall 56 of box 50; and this flange 54, instead of having gear teeth like the part 11, is formed with a peripheral sector 57, which presents a pair of oppositely fac-

ing abutments 58 and 59. A ring 60 of insulating material is rotatably mounted against the back wall 56 with its single tooth or lug 61 projecting radially inward in the path of rotation of the sector 57. Thus, when the handle 5 is inserted 5 in the pocket 52, 53 and turned in clockwise direction, the abutment 58 picks up the lug 61 and rotates the ring 60 until the handle has completed its full turn so as to be removable from the box 50. The ring 60 carries on its back 10 face a metallic insert 62, dimensioned for continuous contact with the cylindrical wall of the box 50 and for engagement of its face with the contact terminal 63, set through the back wall 56, as seen in Figure 12. The lug 61 and the abutment 58 are so related to the pocket 52, 53 that upon completion of a single turn of the handle member 5 therein, the insert 62 is shifted into registration and contact with the terminal 63, closing the circuit of a burglar alarm, such as 15 indicated at 64.

It is the intention that this alarm box 50 shall be installed at an intermediate position in the total series, so that it may appear to be one of the standard boxes like the box 40 which the 20 watchman is required to visit regularly; thus, even under surveillance, he can visit the box 50 and turn in the alarm without arousing suspicion. And since the key member 34^x is fixed in the hub 51 of the pocket 52, 53 so as to turn 25 with the pocket, the operation of the handle 5 in the box 50 will not rotate the plug 24^a of the cylinder lock, and will not modify the adjustment of the plungers 29; hence, the handle member 5 is maintained in condition to operate 30 in the next regular box 40 of the series, just as it would have operated if the watchman had not visited box 50.

Thus, in the emergency just described, the 35 watchman will leave the box 50 with the contact 40 elements 62 and 63 in operative relation, so that the alarm will continue to sound for summoning help while the watchman continues on his rounds. When the emergency is past, the handle 5 may be inserted in the box 50 and by rotation in 45 counter-clockwise direction will cause the abutment 59 of sector 57 to turn until it engages the lug 61 of the ring 60 and then in the final portion 50 of the turn of the handle 5 the ring 60 will be shifted to carry the insert 62 to the position 55 indicated in dotted outline in Figure 13 and out of engagement with the terminal 63, thus opening the circuit.

To prevent operation of the winding gear 11 otherwise than by means of the handle 5, the 55 gear is normally locked against rotation by a series of spring-pressed tumblers 70 carried in suitable bores formed in a special boss 71 projecting from the back wall 13 of the housing 12. Pocketed within the gear 11 is a set of plungers 60 65 72, each registering with one of the tumblers 70, as seen in Figure 4. The plungers 72 may be of various lengths, or may project by different amounts from the face of the gear 11, and they are disposed in the portion of that face which lies between the walls 16, 16 and thus forms an end wall for the pocket into which the handle 5 is to be inserted. In the end of the portion 21 of the handle member there is formed a series of recesses 73 corresponding in depth to the 70 lengths of the respective plungers 72, so that when the handle member is inserted in the pocket the plungers 72 are depressed just sufficiently to force the tumblers 70 back of the plane at which the gear 11 contacts with the back wall 13. In 75

this manner the gear is unlocked from the back wall and may be rotated by the turn of the handle 5 in the manner already described. This prevents unauthorized rotation of the winding gear 11 by any means other than the particular handle 5, which is designed for that purpose, and practically insures that the watchman shall send in his reporting signals only in the authorized manner.

10 Similar locking means is provided in the box 40 in which a pocket 42, 43 is provided for the reception of the handle member 5, and is rotatably mounted by the journaling of its back wall or flange 41 on the boss 14^a. In this case the part 15 41 carries no teeth like the gear member 11, but it does include suitable locking bores for engagement with the tumblers 78 carried in the boss 44 on the back wall 13^a of the box, and it also carries a set of plungers 72, which cooperate with 20 the recesses 73 in the end of the key member 5 to release the flange 41 and its connected pocket 42, 43 for rotation in the box 40. And, similarly, the alarm box 50 is provided with locking tumblers 70 and plungers 72 to cooperate with the 25 handle member when it is inserted in the alarm box. This tends to prevent tampering with the system by making it practically impossible to employ a handle borrowed from another system, since the arrangement of the plungers 72 represents a particular combination assigned to only 30 one system and one handle member 5 of this type.

Referring to the mechanism for changing the arrangement of plungers 30 in the recesses 29 of the handle member 5, and particularly to Figure 35 8, which shows a single tooth 27 carried by the disk 26 for operating the gear wheel 28, it may be understood that I do not limit myself to this specific structure. For example, if the system should include only five stations instead of ten, 40 as assumed herein, the cylinder 32 might be arranged with only five sets of holes disposed at equi-angular positions in the cylinder, and the disk 26 could be provided with two teeth instead of one, so that in its single revolution it would 45 shift the gear 28 through an angle occupied by two of its teeth, or one-fifth of a turn; and, obviously, other gear ratios may be provided between the cylinder 32 and the key-operated plug 24^a as required by the conditions of each individual 50 installation of a system.

Figure 14 shows a modified construction for the ward ribs which are inter-engaged by the notches 29 of the handle 5. Instead of casting these ribs integrally in each of the boxes 12 and 40, the ribs 55 5 may be made as separate members 18^x and assembled with spacer rings 80 interposed so as to position the ribs 18^x wherever wanted for providing the various combinations by which the several boxes of the system differ from each other. 60 The ribs 18^x and their spacer rings are secured in place by a threaded clamping ring 81 with a lock ring 82 added to prevent any loosening of the parts in use.

While there is shown and described herein certain specific structure embodying the invention, it will be manifest to those skilled in the art that various modifications and re-arrangements of the parts may be made without departing from the spirit and scope of the invention, and that the 70 same is not limited to the particular form herein shown and described, except in so far as indicated by the appended claims.

I claim:

1. In a system including a series of stations 75 with a watchman's box at each station, signal

mechanism in certain of the boxes, a removable operating handle for said mechanism, each box having ward means differing from the ward means of the other boxes of the series, tumblers carried by the handle projecting in positions to 5 register with said ward means, a control member shiftable in the handle to a series of positions each corresponding to one box of the series, said member serving at each position to lock one or more tumblers in projected position and to release 10 one or more tumblers for yielding encounter with the wards of the corresponding box so as to allow manipulation of the handle therein, together with a single key-operated lock secured in the handle and connected for shifting said control member 15 from one position to another, and similar keys mounted fixedly, one in each box of the series, for engaging the lock and causing said control member to be shifted as the handle is actuated in each box. 20

2. In the combination defined in claim 1, said actuation of the handle being a rotation about an axis through the key, the tumblers projecting radially from the handle, and said ward means being spaced from the axis of rotation for engaging selected tumblers of the handle as it turns in the box. 25

3. In the combination defined in claim 1, the actuation of the handle being a rotation thereof about an axis through the key, the tumblers projecting radially from the handle, the ward means being spaced from the axis of rotation, and the control member in the handle comprising a cylinder rotatable therein and having variously disposed recesses in its surface arranged to register with different tumblers or groups of tumblers at different positions in the rotation of the cylinder, each tumbler having a spring normally holding it in projected position and the registration of a recess of the cylinder rendering a tumbler yieldingly compressible upon encountering a ward as the handle is turned in the box. 30 35 40

4. In the combination defined in claim 1, the actuation of the handle being a rotation thereof about an axis through the key, the tumblers projecting radially from the handle, the ward means being spaced from the axis of rotation, the control member in the handle comprising a cylinder rotatable therein and having variously disposed recesses arranged to register with different tumblers or groups of tumblers at different positions in the rotation of the cylinder, and the key-operated lock comprising a rotatable part with a one-way driving connection therefrom to rotate the apertured cylinder for shifting one or more different recesses thereof into registration with corresponding tumblers each time said lock part is rotated in the handle. 45 50 55

5. In the combination defined in claim 1, the actuation of the handle being a rotation thereof about an axis through the key, the tumblers projecting radially from the handle, the ward means being spaced from the axis of rotation, the control member in the handle comprising a cylinder rotatable therein and having variously disposed recesses arranged to register with different tumblers or groups of tumblers at different positions in the rotation of the cylinder, and the key-operated lock being geared to rotate the recessed cylinder through a limited angle for shifting one or more different recesses thereof into registration with corresponding tumblers each time the lock is turned through a full revolution in the handle, such full revolution being neces- 60 65 70 75 80 85 90 95 96

- sary to permit disengagement of the lock from the key of any box of the series.
6. In the combination defined in claim 1, the signal mechanism in certain of the boxes including a rotatable member having a pocket of non-circular cross-section fitting the cross-section of the handle whereby engagement of the handle in said pocket effects a driving connection through which the member may be rotated by the handle,
- 10 the key of the box being fixed substantially at the axis of rotation and the lock in the handle being disposed for operative engagement with the key when the handle is inserted in the pocket, together with means carried by said rotatable member for operating a signal mechanism when it is rotated whereby rotation of the handle in said signal box serves to transmit the signal and to shift the control member of said handle by rotation of the lock relatively to the fixed key.
- 20 7. In the combination defined in claim 1, an auxiliary box closely resembling other boxes of the series and located for optional inclusion in the series by the watchman in making his rounds, said box including an alarm switch with actuating means therefor having a pocket of non-circular cross-section fitting the cross-section of the handle whereby upon engagement of the handle therein said means may be rotated by the handle, said alarm box having a key cooperable
- 25 with the lock in the handle but mounted to rotate with said pocket of the actuating means to avoid shifting the control member and changing the arrangement of tumblers when the handle is optionally employed to actuate the alarm switch.
- 30 8. In the combination defined in claim 1, each box including a rotatable member within the box having a pocket of non-circular cross-section fitting the cross-section of the handle to be engaged and rotated by the handle when inserted
- 35 therein, together with a locking device normally holding said member against rotation, the locking devices of all boxes of the system being alike, and lock releasing means cooperable therewith carried by the handle, said locking device and releasing means being individual to the system and the operation thereof being essential to the actuation of the handle in each box of the system.
9. In the combination defined in claim 1, said operating handle including a cylindrical portion and a laterally extending portion in which the tumblers are carried and each box including a rotatable member having a pocket comprising a circular portion to receive the cylindrical 15 portion of the handle and a laterally extending portion to engage the lateral part of the handle so that the handle may operate to turn the rotatable member within the box, locking tumblers normally holding said rotatable member 20 against rotation with actuating means for said tumblers exposed in the lateral portion of the pocket, the laterally extending part of the handle having areas engageable with said actuating means positioned to effect the release of the 25 tumblers when the handle is inserted in operative position in the pocket.
10. In the combination defined in claim 1, said manipulation of the handle being a rotation thereof and the ward means comprising one or 30 more ribs in each box spaced around the axis of rotation, said ribs being separate similar members secured in said boxes with spacers positioning them axially therein whereby said ribs and spacers may be readily assembled in any desired arrangement in each of the boxes of a 35 series.

HAROLD MACHINIST.
